PACKAGING MACHINE

Daniel Belcher, Minneapolis, Minn., assignor to
 Bemis Bro. Bag Co., Minneapolis, Minn., a corporation of Missouri

Application April 21, 1938, Serial No. 203,336

5 Claims. (Cl. 226—61)

This invention relates to new and useful improvements in packaging machines, and more particularly to machines adapted for packaging sugar, flour, and various other finely ground or 5 comminuted materials.

Empty paper bags, as now commonly made on bag making machinery, whether of the in-tucked or flat type, usually have their walls folded into flatwise relation to facilitate stacking and storage. In most instances, the bottom of the bag is flat and the bag walls are so folded that the bag bottom is disposed in a plane parallel to the plane of the flattened walls of the bag body. Because of the bag bottoms being folded into 10 flatwise relation with respect to the walls of the bag body, when the bag is to be filled, the walls and bottom thereof are usually expanded or at least, partially expanded by the operator before or while slipping the empty bag over the filling 15 tube to receive a charge. The bag bottom does not usually assume its normal position without aid from the operator, because of the inherent nature of the material which, in order to provide sufficient strength, has some degree of stiffness. 20 The operator then manually manipulates or taps the walls of the bag body with the hand or fingers, during the filling operation, to cause the bag walls and bottom to assume their normal positions so that the bag may receive its full charge, and 25 whereby the bag body will be properly shaped. This necessitates the constant services of an operator to watch each bag as it is fitted onto the filling tube to see that the walls and bottom of each bag are expanded to their normal positions, 30 before the bag is completely filled. This requires additional labor and time, and decreases the output of the operator.

It is therefore desirable that means be provided in connection with a packaging machine, 35 for positively expanding the walls and bottom of the bag body to their normal positions and shaping the bag body, before the bag receives its charge, so that when the empty bag has received a full charge of material, its body will be neatly 40 shaped and all of the filled bags will be substantially identically the same in appearance.

A feature of the present invention, therefore, 45 is to provide in combination with a packaging machine, means for positively expanding and shaping the walls and bottom of the bag body, before a charge is delivered into the empty bag.

A further object is to provide a packaging machine comprising a pair of relatively movable elements adapted to be received in the mouth of 50 an empty bag, and having means for normally

retaining them in retracted position, whereby an empty bag may readily be slipped or fitted thereover, after which they are released and permitted to engage the walls of the bag mouth with sufficient tension to support the bag thereon, while 5 pressure is introduced into the empty body of the bag to expand the walls and bottom thereof to their normal positions before the bag is filled.

A further object is to provide means for expanding the walls and bottom of an empty bag 10 and shaping the bag body by air pressure, prior to filling the empty bag.

Other objects and features of the invention reside in the novel construction of the means for supporting the empty bag while expanding the 15 walls and bottom thereof by air pressure; in the construction of the means for automatically releasing the bag from its supporting means, after it has received a predetermined charge of material; in the novel means for retaining the bag 20 supporting means in inoperative or contracted position, whereby an empty bag may readily be fitted thereover, and which retaining means is provided with a conveniently located release lever adapted to be engaged by the operator's hand, 25 in the operation of slipping the bag onto the bag supporting elements or jaws, whereby said retaining means is rendered inoperative to permit the bag supporting means to move into operative engagement with the walls of the bag mouth with 30 sufficient tension to frictionally support the bag thereon; in the novel means provided for introducing a blast of air into the empty bag, thereby to expand its walls and bottom and shape the 35 bag body before the empty bag receives a charge; and, in the novel construction and arrangement of the various parts of the mechanism, which are extremely simple and inexpensive, and results in the production of an apparatus of the character disclosed, which requires but a single operator to feed the empty bags thereto, and whereby the collapsed walls and bottom of each bag are automatically expanded into their normal positions and the bag body shaped, before a charge 40 is delivered into the empty bag.

Other objects of the invention will appear from the following description and accompanying drawings and will be pointed out in the annexed claims.

In the accompanying drawings there has been disclosed a structure designed to carry out the various objects of the invention, but it is to be understood that the invention is not confined to the exact features shown as various changes may 50 55

be made within the scope of the claims which follow.

In the drawings:

5 Figure 1 is a view partially in section, showing the means for supporting the bags in inoperative and operative positions;

10 Figure 2 is a fragmentary detail view showing the trip lever operated to release the bag supporting elements;

15 Figure 3 is a vertical sectional view substantially on the line 3—3 of Figure 4, showing the means for introducing pressure in the empty bag to expand its walls, and also showing the driving mechanism for the rotary supporting member;

18 Figure 4 is a plan view of Figure 3;

Figure 5 is a detail sectional plan view on the line 5—5 of Figure 3;

Figure 6 is a detail sectional view on the line 6—6 of Figure 3;

20 Figure 7 is a sectional plan view on the line 7—7 of Figure 3;

Figure 8 is a detail sectional view on the line 8—8 of Figure 3, showing a portion of the driving means;

25 Figure 9 is a detail sectional view on the line 9—9 of Figure 4;

Figure 10 is a perspective view showing the normal condition of the bag walls before they are expanded; and

30 Figure 11 is a view showing an air control means of modified construction.

The novel apparatus herein disclosed is shown comprising a main supporting structure, including upper and lower spider-like frame members 35 2 and 3, secured together in vertically spaced relation by a plurality of rods 4, 5, and 6, as best shown in Figures 3 and 7.

40 A tubular supporting member 7 is shown mounted on the upper frame member 2 and has two or more legs 8 whose lower ends are seated upon the frame member 2 and suitably secured thereto by such means as bolts 9. A hollow shaft 11 is rotatably mounted within the tubular supporting member 7 and has secured to its upper end, an annular or ring-like member 12, shown in Figures 3 and 4. A suitable thrust bearing 13 is preferably interposed between the hub 14 of the annular member 12 and the upper end of the tubular support 7, to carry the weight of the hollow shaft 11 and member 12.

45 An important feature of the present invention resides in the means provided for expanding the walls and bottom of the empty bags by air pressure, prior to filling the bag. To thus expand the walls of the empty bag, means is provided on the annular member 12 for supporting the bag while introducing a blast of air therein of sufficient force to expand the walls and bottom thereof and, at the same time, shaping the bag body.

55 The means provided for thus supporting the empty bags on the annular member 12, is shown comprising an element 15 having its upper end suitably secured to the member 12 by such means as bolts 20. The element 15 is substantially U-shaped in cross section, as best shown in Figure 5, and its upper end is open and adapted to register with an opening 16 provided in the annular member 12, as best shown in Figure 9.

60 70 A complementary element 17 is pivoted at 18 to the member 15. The member 17 is also substantially U-shaped in cross section and is preferably slightly smaller than the element 15, whereby its side walls may be received between the corresponding side walls of the member 15, whereby

said elements cooperate to provide a hollow structure, as clearly illustrated in Figure 5.

75 The element 17 is shown provided with an inwardly extending arm 19 having a shouldered stud 21, upon which is mounted a suitable roller 22. A spring 23 is shown having one end connected to the upper end of the stud 21 and its opposite end to a rod 24, supported in spaced flanges 25, which may be integrally formed with the cross arms 26 of the annular member 12. The spring 23 constantly urges the pivoted element 17 in an inward direction, or into bag supporting position, as will readily be understood. A suitable stop, not shown, may be provided for limiting the inward movement of the element 17.

10 The means for supplying air to the bag is best shown in Figure 3, and comprises a suitable fitting 27 supported by an arm 28, shown adjustably secured to the upper end of the rod 4 by an adjusting screw 29. The fitting 27 is shown having a flange 31 at its lower end, to which may be secured a suitable packing or gasket 32 adapted to engage the upper finished surface of the annular member 12 in substantially leak-proof relation. One end of a suitable air supply conduit 33 is connected to the fitting 27. The opposite end of the conduit 33 may be connected to a suitable blower 34 driven by a motor 35, shown supported on the lower member 3 of the main frame of the apparatus. When the blower 34 is operated, air will be delivered into the conduit 33, and when the fitting 27 registers with the opening 16 in the annular member 12, as indicated in dotted lines in Figure 9, a blast of air will be introduced into the empty bag 30, supported on the elements 15 and 17, whereby the bag walls are expanded, as shown in Figure 3 in dotted lines.

15 As best shown in Figure 4, the apparatus may comprise a plurality of stations, A, B, C and D, in which A represents the feeding station, where an operator slips the empty bags onto the bag supporting elements 15 and 17; B the bag-expanding station or location, where a blast of air may be introduced into each empty bag; C the filling station where a predetermined charge of material is delivered into each bag; and D the unloading or delivery station, where the filled bags are discharged onto a suitable receiving means, such as a table or conveyer, generally indicated by the numeral 36.

20 The pivoted element 17 must be swung into or towards the member 15, as shown in Figure 1, before an empty bag can be fitted over the lower ends of the members 15 and 17. Means is therefore provided for holding the member 17 in the position shown in Figure 3, while the operator at station A feeds or slips an empty bag over the lower ends of the elements 15 and 17.

25 The means provided for thus retaining or locking the element 17 in inoperative position, is best shown in Figures 1 and 2 and comprises a dog 37 mounted on a pivot 38 and having one end adapted to engage a projection 39 on the element 17, thereby to lock said element in the position shown in Figure 2. The dog 37 has a suitable spring 40 normally holding it in the position shown in Figures 1 and 3. The opposite end portion 41 of the dog 37 is positioned to be engaged by a finger 42 secured to a small shaft 43, shown rotatably mounted in suitable bearings provided in the flanges 25 of the cross arms 26 of the annular member 12. Suitable trip levers 44 are shown secured to the ends of the shaft 43 and are normally engaged with the ends of the rod 24, as clearly illustrated in Figures 1 and 6. When the

above the described parts are in the positions shown at the right hand side of Figure 1, it will be noted that the dog 37 is lockingly engaged with the projection 39, whereby the element 17 is locked in retracted position. This is the position assumed by the elements 15 and 17, when they reach station A.

The operator then grasps an empty bag, such as shown in Figure 10, and opens the mouth or top thereof sufficiently to permit it to be slipped over the lower end of the elements 15 and 17, and into engagement with a horizontal flange 45 shown provided on the fixed element 15. The flange 45 merely serves to limit the upward movement of the empty bag on the elements 15 and 17. As the operator slips the bag upwardly onto the elements 15 and 17, he will actuate one of the trip levers 44 and move it upwardly to the position shown in Figure 2, whereby the dog 37 is moved out of locking engagement with the projection 39. When the dog 37 is thus disengaged from the projection 39, the spring 23 will swing the pivoted element 17 into its operative position shown in Figures 1, 2, and 3, whereby the bag mouth is expanded and the bag frictionally held on the members 15 and 17 by the tension exerted on the pivoted member 17 by the spring 23. The annular member 12 is then rotated a portion of a revolution whereby the empty bag which has just been placed on the elements 15 and 17, will come to rest at station B. In the next operation of the member 12, the openings 16 thereof, which is positioned at station B in Figure 4, and beneath which a bag is suspended, will pass beneath the fitting 27, whereby it will momentarily communicate therewith. Such communication between the fitting 27 and opening 16 will cause a blast of air to be introduced into the empty bag, whereby its walls and bottom are expanded before the bag comes to rest at station C. By locating the fitting 27 between stations B and C, the flange 31 thereof will cooperate with the opening 16 in the member 12 to provide, in effect, a valve which is momentarily opened, for each movement of the member 12, thereby to introduce air, under pressure, into each bag as it passes from station B to station C.

At station C each bag receives a predetermined charge of material from a suitable hopper 46, shown supported over the annular member 12 by a bracket 47 secured to the upper end of the rod 6 of the main frame. The hopper 46 is in communication with a suitable weighing mechanism, not shown, by means of a conduit 48, partially shown in Figure 1. The lower end of the hopper is shown having a flange 49 to which is secured a suitable packing or gasket 51, which serves to seal the joint between the lower end of the hopper and the upper surface of the annular member 12 in a manner similar to the fitting 27.

In some instances, it might be found desirable to provide a suitable table or support 50 beneath the hopper 46, to carry the weight of the filled bag, should it accidentally become detached from the elements 15 and 17 before it reaches station D. If desired, the table 50 may be extended under station B to prevent the empty bag from being blown off the elements 15 and 17, when pressure is introduced in the bag to expand its walls. Proper regulation of the air pressure, however, will avoid this. The table may be supported on the rod 6, as shown in Figure 4, whereby it is adapted for vertical adjustment.

Means is provided for contracting or moving

the pivoted element 17 from its operative position, shown at the right hand side of Figure 1, to its inoperative position, shown at the left hand side of Figure 1. The means provided for thus returning the pivoted element 17 to its bag receiving position, is best shown in Figures 3 and 4, and comprises a suitable cam 52 which may be integrally formed with the upper end of the tubular support 1 or otherwise secured thereto. The cam 52 is adapted to be engaged by the roller 22 of the pivoted member 17, as shown in Figure 3, whereby the member 17 is moved outwardly against the tension of the spring 23 until the spring 40 of the dog 37 swings said dog into locking engagement with the projection 39 of the element 17, as shown in Figure 1. The cam 52 is so arranged with respect to station D, that when the filled bag, shown at the right hand side of Figure 1, reaches a certain position over the conveyer 36, the roller 22 will engage the cam 52 and thereby actuate the member 17 to release the bag, whereby the latter drops by gravity onto the conveyer 36, which conveys it to a suitable receiving means such, for example, as a bag shaker or suitable receiving table.

The cam 52 is so shaped that by the time the elements 15 and 17, which have just discharged a bag onto the conveyer 36, are returned to station A, the pivoted member 17 will be locked in the position, shown at the left hand side of Figure 1, whereby the operator may readily feed or slip another empty bag onto the lower ends of the members 15 and 17, as shown in Figure 1. The operator will, as previously stated, release the pivoted member 17 by upwardly swinging one 35 or both of the trip arms 44, in the operation of feeding the bag onto the elements 15 and 17, whereby the element 17 is swung into engagement with the bag walls, as shown in Figure 2, by the action of the spring 23, thereby to frictionally support the empty bag thereon.

The means provided for operating the annular member 12 is best shown in Figures 3 and 8, and comprises a suitable drive shaft 53, shown axially mounted in the main frame of the apparatus in suitable bearings provided in the frame members 2 and 3. The shaft 53 is shown extending upwardly through the tubular supporting member 1, and may have its upper end connected to and operating a mechanism (not shown) for supplying material to the hopper 46, and whereby the mechanisms will operate in timed relation relatively to one another. The shaft 53 is adapted to be constantly rotated by the motor 35, which preferably is provided with a suitable speed reducer 54 having a shaft 55 to which is secured a suitable sprocket 56. A chain 57 operatively connects the sprocket 56 to a sprocket wheel 58 secured to a shaft 59 mounted in suitable bearings 61 and 62, shown secured to one of the radial arms of the lower frame member 3. A bevel pinion 63 is shown secured to one end of the shaft 59 and meshes with a similar pinion 64 secured to the drive shaft 53.

A gear wheel 65 is keyed to the shaft 53, above the frame member 2, and is shown meshing with a gear 66 mounted on a stud 67. The gear 66 carries a crank pin 68 which is received in a slot 69 provided in an arm 71 mounted for pivotal movement upon a suitable stud 72 secured to the frame member 2.

The arm 71 is shown provided with a gear segment 73 which meshes with a gear segment 74 having a hub 75 loosely or rotatably sup-

ported upon the vertical drive shaft 53. The hub of the gear segment 74 is shown provided with an arm 76 which carries a spring-actuated dog 77 adapted to engage a ratchet 78, secured to the tubular shaft 11 below the lower end of the hollow support 1, as shown in Figure 3.

In the apparatus, as herein disclosed, four stations are provided, and the annular member 12 is therefore rotated one-fourth of a revolution or 10 90° for each oscillation of the crank arm 71. The ratchet 78 accordingly has four notches 79 in its periphery adapted to be engaged by the dog 77, as shown in Figure 8. The dog 77 is shown provided with a suitable spring 81 for constantly 15 urging it into engagement with the periphery of the ratchet 78.

To prevent over-running of the member 12, a suitable stop member 82 is shown pivotally supported on a lug 83 provided on the lower 20 end of the hollow support 1. The hub 84 of the stop member 82 is disposed above the ratchet 78 and has a depending portion 85 adapted to be received in notches 86 provided in the periphery of the ratchet 78. A spring 87 is shown 25 engaged with the opposite end portion 88 of the stop member 82 and constantly urges the end portion 85 thereof into engagement with the periphery of the ratchet 78.

By referring to Figure 8, it will be noted that 30 the end walls of the notches 86 in the periphery of the ratchet 78 are substantially parallel, whereby the ratchet is locked against movement in either direction, when the depending end portion 85 of the stop member 82 is positioned in 35 one of the slots 86. It is therefore necessary that means be provided for positively moving the end portion 85 out of the slot 86 in which it may be received, before the ratchet can be rotated by the dog 77 on the arm 76. The means provided for thus moving the end portion 85 of the 40 stop member 82 out of engagement with the ratchet 78, is shown comprising a pin 89 secured to the gear segment 74 and positioned to engage an inwardly projecting cam or lug 91 45 provided on the stop member 82, as best shown in Figure 8. The pin 89 is so related to the cam or lug 91 that it will engage the cam 91 and swing the end portion 85 out of engagement with the 50 notch 86 of the ratchet just before the dog 77 engages the next notch 79 in the ratchet, to impart rotary movement to the member 12.

In Figure 11, there is shown a valve mechanism which may be used for controlling the supply of 55 air to the bag at station B, or at any other location between stations A and C. In the form here shown, a butterfly valve 91 is shown provided within the fitting 92 which corresponds to the fitting 27, shown in Figure 3. The shaft 93 60 which supports the butterfly valve 91 is shown provided with an arm 94 adapted to be engaged by pins 95 carried on the annular member 12. The hub of the arm 94 is shown provided with an upwardly extending arm 96, to which one end 65 of a suitable spring 97 is secured. The opposite end of this spring is shown fixed to a lug 98 on the fitting 92, whereby the upper arm 96 is normally held against the stop pin 99, thereby to retain the valve 91 closed.

70 The valve 91 is opened when the pin 95 carried by the rotary member 12 engages it and swings said arm from the full to the dotted line position, shown in Figure 11. The pin 95 is so positioned with respect to the arm 94 of the butterfly valve, 75 that when the annular member 12 comes to rest

in the position shown in Figure 4, the pin 95 will move out of engagement with the arm 94 and thereby permit the butterfly valve to close by the action of the spring 97.

The novel apparatus herein disclosed has proven very efficient in operation. It requires but one operator. This operator is stationed at station A, and merely feeds or slips the empty bags onto the lower ends of the bag supporting elements 15 and 17, each time the annular member 10 12 comes to rest. In the present instance, four sets of bag supporting elements 15 and 17 are shown provided on the annular member 12, and four bags are therefore expanded or opened for each revolution thereof. 15

The invention is shown embodied in the construction of a bag filling machine, whereby a complete packaging machine or apparatus is provided which expands the empty bags, fills the bags, and discharges the filled bags onto a suitable 20 receiving conveyer. The operation of the apparatus requires but a single operator whose duty it is to slip the empty bags over the bag supporting elements 15 and 17. All of the other operations required to expand or open the empty bags by air 25 pressure, filling the bags, and discharging the filled bags onto the conveyer 36, are accomplished automatically.

It will also be noted that, as shown in the drawings, the annular member 12 is adapted for intermittent operation. It is to be understood that, in some instances, it may be found more desirable to operate the member 12 at a continuous speed, and I therefore do not wish to be limited to an intermittently operable apparatus. 30 35

The particular location of the air supply means or fitting 27 may also be varied without departing from the scope of the invention. For example, in some installations, it may be found more desirable to locate the fitting 27 adjacent to or at station A, and so arrange it that each time a bag is slipped onto the elements 15 and 17 at station A, a blast of air is introduced into the bag to expand its walls. 40

I claim as my invention:

1. In an apparatus of the class described, a movable member having an opening therein, an element fixed to and depending from said member and having its lower end portion adapted to be received in the mouth of an empty bag, a complementary element mounted for pivotal movement with respect to said fixed element and having its lower portion adapted to be received in the mouth of the bag and cooperating with said fixed element to provide a filling spout adapted to support a bag, said spout being in communication with said opening, a conduit connected with a supply of air under pressure and having its discharge end normally closed by said movable member, and means for operating said member whereby when the opening therein passes the air supply conduit, a blast of air is directed into the bag supported on said elements, thereby to expand the walls and bottom of the bag and shape its body. 50 55 60 65

2. In an apparatus of the class described, a movable member, an element fixed to said member and depending therefrom, a complementary element mounted for pivotal movement adjacent to said fixed element, the lower portions of said elements being adapted to be received in the mouth of an empty bag and cooperating to frictionally support the bag, when said elements are expanded, means for retaining said elements in retracted position to permit an empty bag to be 70 75 80 85 90 95 98

fitted over the lower ends thereof, manually operable means for releasing said retaining means whereby said members may expand into frictional engagement with the walls of the bag mouth, 5 thereby to frictionally support the empty bag on the lower ends thereof, pneumatic means for expanding the walls and bottom of the empty bag while supported on said elements, and means for automatically contracting said elements to release the bag therefrom.

3. In an apparatus of the class described, a member mounted for rotary movement and having an opening therein, an element fixed to said member and substantially U-shaped in cross section, and a second element mounted for pivotal movement with respect to said fixed element and also substantially U-shaped in cross section, one of said elements being relatively smaller than the other, whereby portions of its walls may overlap 20 portions of the walls of the other element, thereby to provide a filling spout, said filling spout being in communication with said opening, means whereby said pivoted element may be swung towards said fixed element to contract the filling spout, means for retaining said elements in contracted position to permit an operator to slip or feed an empty bag over the lower ends thereof, means whereby said retaining means may be rendered inoperative when an empty bag is fitted 25 onto said elements, thereby to permit them to move into engagement with the walls of the bag mouth to support the bag thereon, and an air supply conduit having its discharge end normally closed by said rotary member and adapted to be momentarily opened, when the opening in said 30 member passes the discharge end of the conduit, whereby a blast of air is introduced in the bag to expand it.

4. In an apparatus of the class described, an 40 annular member mounted for rotary movement, a plurality of elements fixed thereto and depending from said member, a supplemental element pivotally mounted adjacent to each fixed element, means constantly tending to swing said pivoted 45 elements outwardly into bag supporting positions, means for locking said pivoted elements in contracted positions, whereby an operator may read-

ily slip an empty bag over the lower ends thereof, a release for each locking means adapted to be engaged by the operator's hand, when slipping a bag onto said elements, whereby said locking means is actuated to release its pivoted element 5 and permit it to move into operative position, whereby it will cooperate with the fixed element to support an empty bag thereon, means for introducing a blast of air into an empty bag supported on said elements, thereby to expand its 10 walls and bottom, means for delivering a predetermined charge of material into the bag while supported on said elements, and cam means for operating said pivoted elements to successively release the filled bags therefrom, and whereby 15 the locking means of said pivoted elements are rendered operative to retain the pivoted elements in bag receiving positions.

5. In an apparatus of the class described, an annular member mounted for rotary movement, 20 a plurality of pairs of bag supporting elements depending therefrom, and the elements of each pair being movable relatively to one another, whereby they may be contracted to permit the mouth of an empty bag to be fitted over their 25 lower end portions, means for expanding said elements into frictional engagement with the walls of the bag mouth, thereby to support the bag thereon, a plurality of stations, means for retaining said elements in contracted positions, 30 whereby an operator at one of said stations may readily slip an empty bag over the lower ends thereof, means adapted to be actuated by the operator to release said retaining means, when slipping an empty bag onto said elements, whereby 35 said elements are moved into frictional engagement with the walls of the bag mouth to support the bag thereon, means at another station for introducing pressure in the empty bag to expand its walls and bottom, means at another station for delivering a predetermined charge of material 40 into each bag as it passes thereby, and means for subsequently actuating said elements to release the filled bag, and whereby said elements are positioned to receive another empty bag. 45

DANIEL BELCHER.
